2 Sheets-Sheet 2

UNITED STATES PATENT OFFICE.

FRANK McLAUGHLIN, OF TORONTO, ONTARIO, CANADA.

TUBULAR DISPENSER.

Application filed February 28, 1924. Serial No. 695,856.

The principal objects of the invention are, to provide a simple form of dispensing device for soap or other materials in paste form which may be manipulated with ease 5 to dispense any desired quantity and which may be discarded without undue waste on the emptying of the container. A further object is to devise a container which will not leak around the discharge 10 end.

The principal features of the invention consist in the novel construction and arrangement of parts, whereby the spindle for operating the piston is held in operative 15 contact with the rotating means by the resistance of the material being dispensed and by the friction of the piston and whereby the piston automatically disconnects from the rotating means when the piston reaches the 20 outward limit of its movement.

A further and important feature of the invention consists in the novel construction of the dispensing closure with a flanged end, whereby the head of the container is sealed. 25

In the drawings, Figure 1 is an enlarged longitudinal sectional view of my improved brush.

Figure 2 is a sectional view of a modified form of brush head connection and dispensing tube. 30

Figure 3 is a sectional detail of a still further modified form of head structure.

Figure 4 is a perspective detail of one of the piston plates. 35

Figure 5 is a perspective view of the top piston plate showing the means for locking the piston to the spindle.

Figure 5^a is a perspective detail of the operating disk for the threaded spindle 40 shown in Figure 1.

Figure 6 is a longitudinal sectional view showing a further modified form of brush.

Figure 7 is a still further modification of the brush head connection.

Numerous forms of fountain shaving brushes have been devised but the structures are complicated and difficult to manipulate and are expensive to manufacture and costly and burdensome to maintain. 45

The main idea in the present invention is to provide a container which when emptied

may be discarded and replaced by a new one, and further to prevent the container from being refilled without a great deal of trouble. 55

In the construction herein shown the container 1 is of tubular form, preferably of thin aluminum and in the form illustrated in Figure 1 it is provided with a flange 2 in double seamed thereto at the bottom end. 60

The upper end is formed with a tapering shoulder 3 terminating in a threaded neck 4, the extremity of which is turned inwardly in a flange 5.

A disc 6 is rotatably arranged at the bottom end of the container resting against the flange 2 and is provided with wing projections 7 to enable it being turned with the thumb and forefinger. 65

A slot 8 is formed in the centre of the disc 7 and into this slot is fitted loosely a flat projection 9 from the lower end of the threaded spindle 10 which extends longitudinally of the container and is threaded with a left hand thread. 70

The piston 11 is formed of cork or any other suitable material engaging the inner wall of the container and having a bottom plate 12 of thin sheet metal threaded on the stem and provided with lug projections 80 13 adapted to extend into and grip the piston. 75

A plate 14 of thin sheet metal is secured to the top of the piston and is provided with one or more spring tongue projections 15 stamped therefrom adapted to be engaged by a pin 16 secured transversely in the top end of the spindle 10 to lock the piston to the top of the spindle when it has been moved out to the end and thereby prevent 90 the refilling of the receptacle.

It will be seen that by the rotation of the disc 6 which engages the flat end 9 of the spindle the spindle is rotated to cause the piston to travel toward the discharge end of the container and when the piston reaches the limit of its outward movement and engages the shoulder 3 of the container, the further turning of the disc 6 causes the spindle to travel through the piston, with drawing the flat end 9 from the disc, thus rendering the piston further inoperative. 95 100

If the piston is pressed downwardly from the top end to cause the end 9 to again engage the disc and the disc is turned backwards the transverse pin 16 engages the tongues 15 and simply turns the piston around, preventing the piston from being drawn down toward the bottom of the container.

The construction of the bottom of the 10 container may be altered in numerous ways, a modification being illustrated in Figure 6.

In the construction herein shown the container is formed with an outwardly turned flange 17 and a packing ring 18 surrounds 15 the container above said flange.

The bottom disc 19 is flanged to extend around the flange 17 and packing ring 18 and is provided with an inwardly flanged end 20 engaging the top of the packing ring 20 and closely encircling the exterior of the container.

The head end of the container is as shown in Figure 1 provided with a threaded cap 21 which threads on to the neck 4 and is 25 formed with an annular recess 22 and a central flanged opening 23.

A dispensing tube 24 of rubber slotted at the top end is provided with a circular base 25 fitting against the inner side of the cap 20 and having an annular bead 26 to fit into the recess 22. This bead holds the flange from lateral displacement when the cap is 30 screwed down against the flange 5 of the threaded neck 4. A perfectly sealed joint 35 is thus effected. The brush head 27 is threaded on to the exterior of the cap 21.

Several variations in the form of the dispensing tube and brush head may be devised.

In Figure 2 a threaded cap 28 is provided 40 with an inturned return flange 29 holding a gasket 30 to engage the flange 5 of the neck. The dispensing tube is formed with a flat flange 31 which engages the flange 29 and the brush head is provided with a flanged 45 extension 32 which is secured to the cap 28 by means of any suitable form of slip fastener, such as a bayonet slot and pin 32'. The flat section 33 of the brush head engages the flange 31 and forms a tight joint there- 50 with.

In the form shown in Figure 3 the top end of the container is formed with an outwardly projecting rib 34 and the brush head is formed with spring fingers 35 adapted to 55 spring over the head to hold the head tightly against the flat flange 31 of the dispensing tube.

In the form illustrated in Figure 6 the upper end of the container is formed with an 60 inwardly bevelled surface 36 above the threaded portion to guide the brush head readily to the thread and above the bevelled portion the neck is flanged inwardly and formed with an outwardly flaring flange 37 forming an annular groove.

The resilient dispensing tube 38 which has a slit 38' in the outer end, is formed with a flat circular flanged portion 39 having a heavy edge bead 40 thereon turned downwardly. This bead is adapted to be stretched 70 over the flange 37 and fits snugly into place and holds the tube thereon when the brush is removed. The brush head is threaded on to the threaded neck of the container and is provided with a flat inner surface adapted 75 to engage the outer side of the flanged portion 39 of the tube to hold it from displacement.

The form shown in Figure 7 differs from that shown in Figure 6, in that the threaded neck 4 is formed with an inwardly turned flange 41 which is cupped on the outward side to receive a bead 42 formed on the flange of the rubber dispenser tube. The flange 41 holds the beaded portion of the tube flange 80 tightly in contact with the brush head which is threaded on to the neck portion and remains in the brush head when same is removed from the container.

Several variations in the detail construction of the joint connection between the brush head and container are herein shown but it will be understood that numerous other forms embodying the same principles may be adopted, so long as the idea of providing 95 a sealing flange on the base of the dispenser tube is adhered to.

A container such as described is extremely simple and inexpensive to manufacture and may therefore be discarded when emptied. 100

What I claim as my invention is:—

1. A dispensing container, comprising a tubular member, a rotatable member closing the bottom of said tubular member and having a slot arranged centrally thereof, a spindle having a flat projection extending into said slot and withdrawable thereon through the rotation of said rotatable member, a piston threaded on said spindle, and resilient means for closing the outer end of the container. 110

2. A dispensing container having an in-turned annular flange at the bottom thereof, a rotatable disc engaging said flange adjacent its outer periphery and retained thereby against outward pressure, a slot in the centre of said rotatable disc, a threaded stem adapted to bear against said disc and having a flat projection extending loosely into said slot, a piston threaded on said stem and adapted to press the material from the discharge end of the container, means for closing the discharge end of the container, and means for locking the piston at the upper end of the container to prevent it from being 120 returned.

3. A dispensing container comprising, a tubular container, a member mounted at the bottom of the container for rotative movement only and being confined against out- 130

ward movement, a threaded spindle detachably and operatively connected with said bottom rotative member, and adapted to bear directly against said rotative member, and
5 a piston sealing said container and threaded on said spindle and having its periphery frictionally engaging the inner wall of said

container to effect a resistance to its outward movement whereby a rearward thrust is imparted said spindle to maintain the same in 10 operative engagement with said rotatable member.

FRANK McLAUGHLIN.
